US0D1085241S

(12) **United States Design Patent** (10) Patent No.: **US D1,085,241 S**
(45) Date of Patent: ** Jul. 22, 2025

(54) **GAMING MACHINE**

(71) Applicant: **Aristocrat Technologies, Inc.**, Las Vegas, NV (US)
(72) Inventors: **Dominic DeMarco**, Round Rock, TX (US); **Bruce Urban**, Las Vegas, NV (US); **Daniel Harden**, Palo Alto, CA (US)

(73) Assignee: **Aristocrat Technologies, Inc.**, Las Vegas, NV (US)

(**) Term: **15 Years**

(21) Appl. No.: **29/854,423**

(22) Filed: **Sep. 23, 2022**

(51) LOC (15) Cl. **21-01**

(52) U.S. Cl.

USPC **D21/369**

(58) **Field of Classification Search**

CLAIM

The ornamental design for a gaming machine, as shown and described.

DESCRIPTION

FIG. 1 is a front perspective view of a gaming machine showing our new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof; and,

FIG. 7 is a bottom plan view thereof.

The dashed broken lines in the figures illustrate portions of the gaming machine that form no part of the claimed design.
